Application April 29, 1955, Serial No. 35,749

Term of patent 14 years

(Cl. D65—1)

FIG-1

FIG-2

Fig. 1 is a side elevation of a submersible sump pump embodying my new design; and

Fig. 2 is a plan view of the submersible sump pump of Fig. 1.

Except as shown in the drawing, the pump is symmetrical, and the portions on the opposite side are essentially the same in appearance as those shown in Fig. 1.

The design is characterized by the features illustrated in full lines in the drawing.

What is claimed is:

The design for a submersible sump pump, substantially as shown and described.
